UNITED STATES PATENT OFFICE.

STEPHEN LANCESKES, OF LOUISVILLE, KENTUCKY.

GRATE.

SPECIFICATION forming part of Letters Patent No. 439,527, dated October 28, 1890.

Application filed April 14, 1890. Serial No. 347,836. (No model.)

To all whom it may concern:

Be it known that I, STEPHEN LANCESKES, a citizen of the United States, residing at Louisville, in the county of Jefferson and State of Kentucky, have invented certain new and useful Improvements in Grates; and I do hereby declare the following to be a full, clear, and exact description of the invention, such as will enable others skilled in the art to which it appertains to make and use the same.

My invention relates to improvements in furnace-grates of that class which employ a series of bearing or supporting bars and a series of removable grate-bars arranged at right angles to the bearing-bars and resting thereon; and the object of my invention is to provide an improved grate in which the grate-bars cannot become displaced or removed from the bearing-bars in cleaning the grate of clinkers, &c., and in which the necessary expansion and contraction of the bearing and grate-bars is provided for.

With these ends in view my invention consists in the peculiar construction and arrangement of parts, as will be hereinafter fully described and claimed.

To enable others to more readily understand my invention, I have illustrated the same in the accompanying drawings, in which—

Figure I is a perspective view showing a grate constructed in accordance with my invention. Fig. II is a longitudinal sectional view of the grate, showing a portion of the bridge-wall and front of a furnace in which the grate is situated. Fig. III is a detail view of the grate-bar removed from the furnace, and Fig. IV is an enlarged detail view to show the interlocking device or loose connection between the overhanging lip and depending hook of the bearing and grate bars.

Like numerals of reference denote corresponding parts in the several figures of the drawings, referring to which—

1 designates the bearing-bars, which are arranged in series transversely across a furnace between the front 2 and the bridge-wall 3 of said furnace, and these bearing-bars are arranged parallel with each other and suitably built into the masonry of the furnace or otherwise supported therein. Each bearing-bar

has a flanged base 4, a vertical web 5, and an overhanging lip 6, which are all made integral with each other, and the overhanging lip or flange is situated at the upper edge of the vertical web and projects outwardly at right angles from the web and on one side only of the same. This lip or flange of each bearing-bar faces the bridge-wall 3 of the furnace, and said flange or lip extends continuously along the upper edge of the bearing-bar, the upper edge of the vertical web and flange being preferably rounded, while the lower face of the flange or lip is at right angles to the vertical face of the web of the bearing-bar.

8 designates the grate-bar. A series of these bars are provided between each pair of adjoining bearing-bars, and these grate-bars span the space between the bearing-bars and rest thereon, the grate-bars being of such length as to rest on the upper edges of the webs of two adjoining bars. Each grate-bar is sinuous or fluted transversely to the length of the same, and as distinguished from prior grate-bars having the lateral faces only of the bar formed with ridges or corrugations my improved bar is made with sinuous or wavy lines in the body thereof. At the front end each grate-bar has a reduced tang 9, while the opposite or rear end of said grate-bar has a depending hook 10, formed on the tang 11 thereof, said tangs 9 11 of the grate-bar projecting from the upper part of said bar, whereby the tangs are adapted to rest on the upper edges of two adjoining bearing-bars, and the body of the grate-bars depends into the space between said bearing-bars, as clearly shown in Fig. II of the drawings. The hook 10 at the rear end of each grate-bar consists of a vertical part and a horizontal part at right angles to said vertical part, and this hook laps over and takes beneath the overhanging lip at the rear side or face of the bridge-wall to prevent the grate-bar from becoming displaced on or disconnected from the bearing-bar. The tang 9 at the front of the grate-bar has two flanges or lugs 12 13 on the lateral faces thereof, one flange being on one face and the other flange being on the reverse face of said tang, and these flanges project or extend beyond the plane of the tang for a

suitable distance. The flanges or lugs are reclined reversely to each other, and they serve to properly space the grate-bars with lateral relation to each other when the grate 5 is built up of the grate-bars. The front ends of the first series of grate-bars have the tangs 9, resting on a support provided on the furnace-front 2, while the rear ends of the first series of grate-bars rest on the first bearing-bar 1, with their depending hooks 10 fitting over and beneath the flange 6 of said bearing-bar 1. The second series of grate-bars rest on the first and second bearing-bars 11, the second series of grate-bars having the front 10 tangs 9 arranged on opposite sides of the first series of grate-bars and with the lateral flanges 12 13 in contact with the rear tangs 10 of the first series of grate-bars to maintain the grate-bars in proper relation to each other.

20 My improved grate can be easily and readily built up within a furnace, and the grate-bars are connected to hold themselves in position against lateral and vertical displacement, which is advantageous, especially when cleaning 25 the grate of clinkers, &c.

The grate and bearing bars are not immovably connected together by the rearward facing-flange 6 and depending hook 10, but the parts are loosely fitted together, so as to allow 30 a slight play without liability to become separated, whereby expansion and contraction of the grate and bearing bars is compensated.

The grate is simple and durable in construction, cheap of manufacture, and the bars can be easily removed when worn out and replaced at a trifling outlay, which advantages are very desirable in a furnace-grate.

I am aware of Patent No. 111,031 for a sectional grate-bar comprising upper and lower sections arranged parallel with each other and connected together at the ends by an expansion-joint; but such is not my invention. My improved grate is differentiated from the 45 grate-bar shown and described in said patent in that I provide a bearing-bar which is arranged below the grate-bars proper, and which bearing-bar is common to all the grate-bars of the series, each grate-bar being made 50 in a single casting and provided at its ends with downwardly-extending tangs to engage a flange on the bearing-bar, whereby the grate-bars proper constitute the entire fuel-bearing surface, and the construction of the grate as

an entirety is materially simplified and its 55 cost of manufacture reduced.

Having thus fully described my invention, what I claim as new, and desire to secure by Letters Patent, is—

1. In a grate, the combination of the series 60 of parallel bearing-bars, which are common to the whole series of grate-bars and arranged transversely below said grate-bars, each bearing-bar having the continuous overhanging flange 6 projecting outwardly from the vertical web thereof at the upper edge of said web, and the series of parallel grate-bars separate from the bearing-bars and arranged at right angles to the same, each grate-bar being provided at both ends with the tangs, 70 which rest on the upper edge of the bearing-bars, the tangs of each grate-bar having the integral depending hooks 10, which take beneath the overhanging flange 6 on the bearing-bar, whereby the grate-bars are held from 75 endwise displacement on the bearing-bars and expansion and contraction between the flange of the bearing-bars and hooks of the grate-bars are provided for, substantially as described.

2. In a grate, the combination of the series 80 of parallel bearing-bars, which are common to the whole series of grate-bars and arranged transversely below said grate-bars, each bearing-bar having the continuous longitudinal 85 flange 6 at the upper edge of the vertical web thereof, and a series of grate-bars separate from the bearing-bars and arranged at right angles to the same, each grate-bar being provided at both ends with the projecting tangs 90 which rest on the bearing-bars, the rear tang of each grate-bar having the integral depending hooks 10, which overlap and take loosely beneath the flange of the bearing-bar, and the front tang of each grate-bar having the 95 laterally-extending lugs or flange 12 13, arranged to contact with the contiguous ends of two adjoining grate-bars to properly space or separate the grate-bars from each other, substantially as described, for the purpose 100 set forth.

In testimony whereof I affix my signature in presence of two witnesses.

STEPHEN LANCESKES.
